US0D1114228S

(12) **United States Design Patent** (10) **Patent No.:** **US D1,114,228 S**
(45) **Date of Patent:** **** Feb. 17, 2026**

(54) **LIQUID DIFFUSING DEVICE**

(71) Applicant: **Aroma Republic Ltd.**, Tel Aviv (IL)

(72) Inventors: **Avner Sadot**, Tel Aviv (IL); **Naomi Kizner**, Tel Aviv (IL); **Guy Dvir**, Ramat Gan (IL)

(73) Assignee: **Aroma Republic Ltd.**, Tel Aviv (IL)

(**) Term: **15 Years**

(21) Appl. No.: **35/519,813**

(22) Filed: **Sep. 28, 2023**

(80) **Hague Agreement Data**

Int. Filing Date: **Sep. 28, 2023**

Int. Reg. No.: **DM/234452**

Int. Reg. Date: **Sep. 28, 2023**

Int. Reg. Pub. Date: **Jan. 26, 2024**

(30) **Foreign Application Priority Data**

Apr. 4, 2023 (IL) 70554

(57) **CLAIM**

The ornamental design for a liquid diffusing device as shown and described.

DESCRIPTION

1. Liquid diffusing device

1.1 is a perspective view;

1.2 is a front view;

1.3 is a back view;

1.4 is a left side view;

1.5 is a right side view;

1.6 is a top view; and

1.7 is a bottom view.

In the reproductions, the broken lines show portions of the product that form no part of the claimed design; The

(Continued)

shadings in the reproductions represent contours only and do not illustrate an ornamentation or decoration on the surface of the product.
